UNITED STATES PATENT OFFICE.

JACOB ZITZERMAN, OF BROOKLYN, NEW YORK.

MOTOR WINDING HANDLE FOR PHONOGRAHS.

Application filed February 25, 1924. Serial No. 695,074.

To all whom it may concern:

Be it known that I, JACOB ZITZERMAN, a citizen of the United States, and a resident of the city of New York, borough of Brooklyn, in the county of Kings and State of New York, have invented a new and Improved Motor Winding Handle for Phonographs, of which the following is a full, clear, and exact description.

10 This invention relates to phonographs and has particular reference to a means for winding the spring motor thereof.

The outstanding object of the present invention resides in the provision of means 15 for housing and concealing the winding handle of a phonograph within the confines of the cabinet, whereby to eliminate the unsightly appearance of the handle which, under present constructions, protrudes from 20 one side of the cabinet, and furthermore to eliminate the handle as an obstruction which prevents the placing of the cabinet close to a wall or other objects.

More specifically the invention 25 contemplates a winding handle which is especially designed for use in connection with a phonograph having a triangular shaped cabinet adapted to fit in the corner of a room.

30 As a still further object the invention contemplates a motor winding handle for phonographs which does not materially increase the cost of manufacture of the machine and which is comparatively simple in 35 its construction.

With the above recited and other objects in view, the invention resides in the novel construction set forth in the following specification, particularly pointed out in the appended claims and illustrated in the accompanying drawings, it being understood that 40 the right is reserved to embodiments other than those actually illustrated herein to the full extent indicated by the general 45 meaning of the terms in which the claims are expressed.

In the drawings—

Figure 1 is a perspective view of a phonograph equipped with a winding handle constructed in accordance with the invention.

Fig. 2 is an enlarged horizontal sectional view therethrough.

Fig. 3 is a fragmentary vertical sectional view taken approximately on the line indicated at 3—3 of Fig. 2.

Referring to the drawings by characters

of reference, 10 designates a phonograph cabinet which is illustrated as of triangular formation, the same being provided with a spring motor 11. The cabinet is provided with a compartment 12 which opens through the front wall of the cabinet and is normally closed by a suitable closure 13. The compartment 12 is arranged alongside of and in a plane coincident with the motor 11. The winding shaft 14 of the motor is provided with a threaded socket 15. The socketed end extends into an opening 16 in one of the side walls 17 defining the compartment 12. The means for winding the motor consists of a crank shaft 18, the eccentric bight 19 of which has rotatably mounted thereon a hand grip or handle 20. One of the terminals 21 of the crank shaft is threaded for engagement within the threaded socket 15 of the winding shaft 14 and the opposite end 22 is positioned in a suitable bearing 23 in the opposite side wall 24 which defines the compartment 12.

Under this construction and arrangement 80 it will be observed that the winding means or handles is arranged within the confines of the phonograph cabinet and is normally concealed from view when the closure 13 is closed whereby to eliminate the unsightly handle which usually projects from a phonograph cabinet. This construction and arrangement further functions to eliminate a projecting winding handle which prevents the disposition of the phonograph close to 85 a wall or another article of furniture. Furthermore the construction and arrangement is particularly applicable to a triangular shaped cabinet which is designed to be positioned within the corner of a room. 90 95

I claim:

1. The combination with a phonograph including a spring motor and a cabinet housing the same having spaced walls within its confines defining a compartment 100 alongside of the spring motor and a U-shaped winding handle disposed within said compartment the bight portion of which defines a hand grip and the free terminals of the leg portions of which respectively extend through bearing openings in the walls of the compartment, one of said terminals being connected with the winding shaft of the motor and the other of said terminals being journaled in the bearing 105 opening of the opposite wall whereby the said winding handle is disposed and oper- 110

able wholly within the confines of the cabinet.

2. The combination with a phonograph including a spring motor and a cabinet 5 housing the same having spaced walls within its confines defining a compartment alongside of the spring motor and a U-shaped winding handle disposed within said compartment the right portion of 10 which defines a hand grip and the free terminals of the leg portions of which respectively extend through bearing openings in the walls of the compartment, one of said terminals being connected with the winding 15 shaft of the motor and the other of said terminals being journaled in the bearing opening of the opposite wall whereby the

said winding handle is disposed and operable wholly within the confines of the cabinet, one of the said outer walls of the cabinet having an opening therethrough constituting a doorway for the compartment and a movable door for closing said doorway. 20

3. The combination with a phonograph including a spring motor and a triangular 25 shaped cabinet housing the motor and adapted to fit within the corner of a room, of a winding handle for said motor disposed and operable within the confines of the cabinet, the said cabinet having a compartment therein opening through its front wall for gaining access to the winding handle in said compartment. 30

JACOB ZITZERMAN.
